CONTROL MEANS OF HYDRAULIC COUPLINGS

Harold Sinclair, Kensington, London, England

Application January 17, 1936, Serial No. 59,520
In Great Britain January 17, 1935

18 Claims. (Cl. 60—54)

The present invention relates to hydraulic couplings of the kinetic type and provided with control means whereby the liquid content of the working circuit of the coupling can be varied 5 while the coupling is operating.

When such couplings are employed for certain purposes, it is desirable to be able to make relatively rapid changes in the liquid content between certain limits, that is to say, changes more rapid 10 than can conveniently be secured with the well-known arrangement of scoop-tube coupling and weir control, as described in my United States Patent No. 1,859,607 with reference to Figs. 1, 2 and 4 thereof.

15 It has previously been proposed to vary the liquid content of hydraulic power-transmitting devices by means of a cylinder which communicates with the hydraulic circuit and in which there is provided a piston, movable by a control member in such a way that liquid can be transferred from the working circuit to the cylinder and vice versa. With this arrangement, when the piston is moved so as to withdraw liquid from the circuit, the cylinder may become charged 20 with a frothy mixture of liquid and gas, owing to the unavoidable entrainment of gas with the working liquid passing through the discharge port or ports of the power transmitting device. In consequence, it has not hitherto been possible to effect accurately measured changes of 25 liquid content by such means.

An object of the present invention is to provide means adapted to effect rapid and accurate changes of liquid content in the working circuit 30 of a hydraulic coupling.

The characteristic curve relating liquid content of a hydraulic coupling to speed of the driven element thereof is not entirely uniform in slope, and a further object of the present invention is 35 to provide control means arranged to compensate for such irregularities.

According to the present invention, in the combination of a hydraulic coupling of the kinetic type with a piston-and-cylinder, or equivalent liquid-storage device of variable capacity (such for example as a bellows device), which is adapted 40 to receive liquid from and force liquid into the working circuit of the coupling, there is provided a gas vent communicating between the upper part of the cylinder or equivalent member of the liquid-storage device and the interior of the hydraulic coupling. Provided that the liquid transfer duct and the vent pipe open into the coupling in such a manner that there is a circulation 45 from the coupling through the duct to

the liquid-storage device and back through the vent pipe to the coupling, gas withdrawn from the coupling, when the liquid content of the circuit is reduced by increasing the capacity of the liquid-storage device, will be rapidly returned 5 from that device to the coupling, so that, except during and immediately after the time when the capacity of the device was varied, there will be a constant relationship between the position of the control member of the device and the quantity 10 of liquid contained therein, for instance, where the device is of the piston-and-cylinder type, between the position of the piston and the quantity of liquid contained in the cylinder. It is not essential that the cylinder or the like 15 should be entirely freed from gas, since the improved arrangement enables the degree of "frothiness" in the cylinder or the like to be rapidly brought to a uniform state for any particular position of the piston or other control member, irrespective of the extent or rapidity of the previous displacement thereof.

The means for varying the capacity of the piston-and-cylinder or equivalent liquid-storage device preferably comprise a cam which is so shaped 20 as to compensate for irregularities in the characteristic curve of the coupling.

Examples of the invention will be described as applied to a hydraulic coupling employed in a boiler plant, to couple, for example, a draught 30 fan or a feed pump to a constant-speed motor, the degree of filling of the coupling being varied to regulate the speed of the fan or pump in known manner.

In the accompanying diagrammatic drawings 35 Fig. 1 is a part sectional side elevation of one embodiment of the invention.

Fig. 2 is a sectional end elevation of a detail on the line 2—2 in Fig. 1.

Fig. 3 is a part-sectional side elevation of a 40 modification of Fig. 1, and

Fig. 4 is a graph showing the characteristics of the coupling in Fig. 1.

Like parts in the several figures of the drawings have the same reference numerals.

Referring to Figs. 1 and 2, a constant-speed electric motor 10 is arranged to drive a driven machine, which in this example is a boiler feed-pump 11, through a hydraulic coupling 12 of the kinetic type having a vaned impeller part 13 45 keyed to the shaft 14 of the motor 10 and a vaned runner part 15 secured to a driven shaft 16 by a key 17 and a nut 18. The shaft 16 is coupled to the pump shaft 19.

A casing 20, fixed to the impeller and shroud- 55

ing the back of the runner, co-operates with an outer casing 21, also fixed to the impeller, to form an annular chamber 22. A fixed manifold 23 surrounds the shaft 18 and carries a scoop tube 24 which opens within the radially outer part of the chamber 22. The scoop tube communicates by an outlet duct 25 formed in the manifold with an outlet pipe 26 leading to a cooler 27, while a pipe 28 connects the cooler to an inlet duct 29 in the manifold, which communicates with the working circuit by ducts 30 in the boss of the runner 18. A series of restricted ports 31 communicate between the working circuit of the hydraulic coupling and the chamber 22.

While the coupling is operating liquid continuously leaks through the ports 31 into the chamber 22 where it is collected by the scoop tube 24 and fed, with some entrained gas, under pressure due to the scooping action, through the cooler 27 and thence back to the working circuit of the coupling. The arrangement so far described is well known.

A pipe 32, branching from the scoop tube delivery pipe 26, leads to a cylinder 33, the axis of which is vertical and which contains a piston 34 adapted to be displaced by suitable control means. The upper end of the cylinder is closed by a conical cover 35 provided with a gas port 36 connected by a pipe 37 to a point in the coupling where the fluid pressure is relatively low; for example, the pipe may lead, as shown in Figs. 1 and 2, to a port 38 in the manifold 23, opening into the radially inner part of the scoop tube chamber 22. This pipe is substantially smaller than the liquid transfer duct 32, and it may be provided with a non-return valve 39.

As already mentioned the characteristic curve relating liquid content of the hydraulic coupling to speed of the driven element thereof is not entirely uniform in slope; consequently under certain conditions of change of load on the boiler, it is necessary to make a somewhat rapid reduction in liquid content of the coupling. There is thus a tendency at such times for an excessive quantity of gas to be sucked through the liquid transfer duct 32 from the coupling into the cylinder 33, with a corresponding reduction in the quantity of liquid. The excess gas is, however, rapidly returned to the coupling through the vent port 36 and pipe 37, being displaced by liquid delivered by the scoop tube 24 to the liquid transfer duct 32, so that the degree of filling of the coupling rapidly attains the desired value. When it is desired to make a rapid increase in the liquid content of the coupling, the piston 34 is merely moved in the required direction, and the necessary quantity of liquid is returned to the circuit, without delay, under pressure due to the force exerted on the piston by the actuating means.

The piston is conveniently actuated by a compressed-air motor, and where a system of automatic combustion control is employed, the compressed air-motor operating the piston may be controlled by means including a cam device so shaped as to compensate for irregularities in the characteristic curve of the coupling.

In the arrangement shown in Fig. 1 the compressed-air motor is of the double-acting type and includes a piston 40 working in a cylinder 41 and coupled to the piston 34 by a rod 42. A slide valve 43 actuated by a rod 44 controls the admission of compressed air from a power supply main 45 to the motor in known manner. The

valve rod 44 is operated through a differential device arranged to compound the effect of a control medium with a return motion from the piston 34.

In the example shown in Fig. 1 the control medium is air under a varying pressure which is supplied to a pipe 46 from an automatic master regulator of known type, indicated diagrammatically at 47. The pressure in the pipe 46 is increased and decreased automatically by the master regulator in proportion to the rise and fall of the load on the boiler plant. To the valve rod 44 is fixed a flexible diaphragm 48 forming the cover of an air-tight chamber 49 communicating with the control air pipe 46. The piston rod 44 extends through a bearing in the bottom 49 of the chamber 48 and is secured to one end of a tension spring 50 the other end of which is adapted to be displaced, in response to movement of the pistons 34 and 40, through the agency of a bell-crank lever 51 mounted on a fixed pivot 52. One arm of the bell-crank lever is pivotally connected to the spring 50, while the other arm ends in a cam follower 53, which is engaged in a cam groove 54 formed in a plate fixed to the piston rod 42.

Fig. 1 shows the servo-motor control mechanism in an equilibrium condition: If the control air pressure in the pipe 46 rises, for example, the upward force acting on the diaphragm 48 exceeds the downward force exerted by the spring 50 so that the valve rod 44 rises, permitting air from the power main 45 to flow to the under side of the piston 40. The pistons 40 and 34 rise in consequence and the cam 54 rocks the bell-crank lever anti-clockwise, so as to increase the tension of the spring 50 and draw the valve rod 44 downward, so that the valve closes as soon as the pistons have risen through a distance appropriate to the change in control air pressure. In a similar way, if the control air pressure falls, the valve rod 44 is drawn downward by the spring 50, with the result that the pistons are caused to descend. The cam 54 now moves the bell-crank lever 51 clockwise, reducing the tension of the spring.

In Fig. 4 the curve A indicates the variation of the speed of the pump 11 (Fig. 1) with the liquid content of the hydraulic coupling, the speed being plotted as ordinate and the values being expressed as percentages of their maximum working limits. It will be seen that over the range of filling from about 50 to 70 percent, the slope of the speed curve is less steep than elsewhere.

Over the part of the range of emptying and filling of the hydraulic coupling where a relatively large variation in liquid content has to be made for a given change in speed of the feed pump 11, it is necessary for the pistons 34 and 40 to travel a relatively long distance for a given variation of the control air pressure. Consequently the part of the cam groove 54 that engages the cam follower 53 over this particular range of travel of the pistons has less slope than the remainder. Thus in the example shown in Fig. 1 the part of the cam groove between the points 54' and 54'' is of reduced slope. It will be obvious that the same effect could be attained by placing the compensating cam mechanism elsewhere, for example in a regulator controlling the air pressure in the pipe 46.

Curve B in Fig. 4 indicates the relationship between the speed of the pump (as ordinate) and the control air pressure. It will be seen that the variation in steepness of the cam groove 54 has

the effect of compensating for the irregularity in the

$$\frac{\text{speed}}{\text{liquid-content}} = \frac{\text{speed}}{\text{control-air-pressure}}$$

5 relationship so as to make the

10 relationship substantially linear.

The arrangement shown in Fig. 1 may be modified as shown in Fig. 3, where a single-acting compressed-air motor is employed. A spring-loaded valve 70 is provided between the outlet pipe 26 and the cooler 27 and is arranged to maintain a fluid pressure of about 7 lb. per sq. in. in the outlet pipe, in the liquid-transfer pipe 32 and in the cylinder 33a above the piston 34a. The lower end of the cylinder 33a serves as the compressed-air motor, the admission and exhaust of air being controlled by a valve 43a actuated by a rod 44a. The valve rod 44a is controlled by a differential pressure device similar in principle to that shown in Fig. 1 and comprising a diaphragm 47 influenced by the control air pressure from pipe 48, a tension spring 50a connected to a bell-crank lever 51a, and a cam 54a co-operating with a cam follower 53a and mounted on the piston rod 42a.

30 When the control air pressure falls and permits air under the piston 34a to be exhausted, the pressure existing in the liquid transfer duct 32 causes the piston to fall so that liquid is transferred from the coupling to the upper end of the cylinder 33a, the gas vent 36, 37 acting as previously described. When the control air pressure rises, air from the power air main 45 forces the piston 34a upward, returning liquid to the coupling. In each case the quantity of liquid displaced is regulated by the differential pressure control device, in accordance with the extent of the change in control air pressure.

I claim:

1. In combination, a hydraulic coupling having a working circuit for coupling liquid, a stationary liquid-storage chamber, control means for varying the capacity of said chamber, a liquid-transfer duct between said chamber and said circuit, and a gas vent debouching from the neighborhood of the top of said chamber and leading to said circuit.

2. In combination, a hydraulic coupling of the kinetic type having a working circuit, a stationary liquid-storage chamber, means for exhausting liquid from said working circuit while said coupling is operating, a duct communicating between said exhausting means and said chamber, control means for varying the capacity of said chamber, whereby said chamber can force liquid into and withdraw liquid from said circuit, and a gas vent opening out of the top of said chamber and leading to the interior of said coupling.

3. In combination, a hydraulic coupling of the kinetic type having vaned impeller and runner members and a scoop member disposed within the coupling so as to engage working liquid therein, at least one of said vaned members being rotatable relative to said scoop member, an outlet duct for discharging liquid engaged by said scoop member, a stationary liquid-storage chamber, control means for varying the capacity of said chamber, said chamber communicating with said outlet duct, and a gas vent opening out of the top of said chamber and leading to the interior

4. In combination, a hydraulic coupling of the kinetic type having a fluid outlet port, a fluid inlet port, and means utilizing the energy of motion of liquid within said coupling for establishing a difference of fluid pressure between said ports, a hydraulic circuit connecting said ports together, said circuit including a stationary liquid-storage chamber having a displaceable wall and a duct leading from the top of said chamber to said inlet port, and control means for displacing said wall to vary the capacity of said chamber.

5. In combination, a hydraulic coupling having a working circuit for coupling liquid, a stationary liquid-storage chamber, control means for varying the capacity of said chamber, a liquid-transfer duct between said chamber and said circuit, a gas port debouching from the top of said chamber, and a duct communicating between said gas port and said circuit, said duct including a non-return valve arranged to prevent flow of fluid through said last-mentioned duct to said chamber.

6. In combination, a hydraulic coupling of the kinetic type having a liquid transfer port, means utilizing the energy of motion of liquid within the coupling for forcing liquid out of said port, and a fluid inlet port opening within said coupling at a point adjacent to the axis of rotation thereof, a stationary liquid-storage chamber, control means for varying the capacity of said chamber, a duct communicating between said chamber and said liquid transfer port, and a duct debouching from the top of said chamber and leading to said fluid inlet port.

7. In combination, a hydraulic coupling of the kinetic type having a liquid inlet port and a liquid outlet port, an auxiliary liquid circuit connected between said ports, means for maintaining a liquid circulation through said auxiliary circuit, a stationary liquid storage chamber, a duct branching from said auxiliary circuit and opening into said chamber, control means for varying the capacity of said chamber, and a vent duct having one end debouching from the upper part of said chamber and the other end communicating with said coupling at a point therein where the pressure is relatively low.

8. In combination, a hydraulic coupling of the kinetic type having a liquid outlet port, a fluid inlet port, and means for maintaining a difference of fluid pressure between said ports, a cylinder having its axis out of the horizontal and its upper end closed, a piston co-operating with said cylinder, control means for actuating said piston, a liquid transfer duct leading from said outlet port and opening into said cylinder above said piston, and a gas vent debouching from the top of said cylinder and leading to said inlet port.

9. In combination, a hydraulic coupling of the kinetic type having a liquid outlet port, a fluid inlet port, and means for discharging liquid from the interior of said coupling through said outlet port, a cylinder having its axis substantially vertical and its upper end closed by a dished member, a piston co-operating with said cylinder, control means for actuating said piston, a liquid transfer duct leading from said outlet port and opening into said cylinder above said piston, and a gas vent debouching from the top of said dished member and leading to said inlet port.

10. In combination, a hydraulic coupling comprising a working circuit, said coupling having a liquid-content runner-speed characteristic of irregular slope, a reservoir communicating with

said circuit, and control means for varying the effective capacity of said reservoir and thereby varying the liquid content of said circuit, said control means comprising a cam so shaped as to compensate for at least part of the irregularity of said characteristic.

11. In combination, a hydraulic coupling of the kinetic type comprising a working circuit, said coupling having a liquid-content runner-speed characteristic of irregular slope, a liquid-storage chamber communicating with said circuit, means for varying the capacity of said chamber and thereby transferring liquid to and from said circuit, a servo-motor for actuating said means, and 15 a cam device operatively connected with said servo-motor and said capacity-varying means, said cam device being so shaped as to compensate for at least part of the irregularity of said characteristic.

12. In combination, a hydraulic coupling of the kinetic type comprising a working circuit, said coupling having a liquid-content runner-speed characteristic of irregular slope, a cylinder communicating with said circuit, a piston slidable in 25 said cylinder to transfer liquid to said circuit, a servo-motor for actuating said piston, control means for starting and stopping said servo-motor, said control means including a cam so shaped as to compensate for at least part of the irregularity 30 of said characteristic, a pressure-responsive device for actuating said control means, and a follow-up connection between said piston and said control means.

13. In combination, a hydraulic coupling of 35 the kinetic type comprising a working circuit, said coupling having a liquid-content runner-speed characteristic of irregular slope, a cylinder communicating with said circuit, a piston slid- 40 able in said cylinder to transfer liquid to said circuit, a fluid-pressure servo-motor for actuating said piston, a control valve for said servo- 45 motor, control means for displacing said valve, and a follow-up connection between said valve and said piston, said connection including a cam so shaped as to compensate for at least part of the irregularity of said characteristic.

14. In combination, a hydraulic coupling of the kinetic type having a liquid-content runner-speed characteristic of irregular slope, said coupling being provided with a liquid transfer port, a fluid inlet port, and means responsive to the motion of liquid within the coupling for maintaining a fluid pressure difference between said ports, a stationary cylinder, a duct communicat- 50 ing between said cylinder and said liquid trans- 55 fer port, a gas vent debouching from the top of said cylinder and leading to said inlet port, a piston slidably fitted in said cylinder, a servo- motor operatively connected with said piston, control means for starting and stopping said servo-motor, said control means including a cam so shaped as to compensate for the irregularity

of said characteristic, and a follow-up connection between said cam and said piston.

15. In combination, a hydraulic coupling of the kinetic type having a liquid-content runner-speed characteristic of irregular slope, said coupling being provided with a liquid transfer port, a fluid inlet port, and means responsive to the motion of liquid within the coupling for maintaining a fluid pressure difference between said ports, a stationary cylinder, a duct communicat- 10 ing between said cylinder and said liquid transfer port, a gas vent debouching from the top of said cylinder and leading to said inlet port, a piston slidably fitted in said cylinder, a servo- 15 motor operatively connected with said piston, control means for starting and stopping said servo-motor, a pressure-responsive device operatively connected with said control means and a return-motion connection which is coupled between said control means and said piston and 20 which includes a cam so shaped as to compensate for at least part of the irregularity of said characteristic.

16. In combination, a hydraulic coupling having a fluid inlet port, a liquid outlet port, and 25 means utilizing the energy of motion of liquid within the coupling for establishing a difference of fluid pressure between said ports, a hydraulic circuit connecting said ports together, said circuit including a stationary liquid storage cylinder 30 and a duct leading from the top of said cylinder to said inlet port, a piston movable in said cylinder for forcing liquid into and withdrawing liquid from said coupling, a servo-motor for actuating said piston, a control member for starting 35 and stopping said servo-motor, and a return-motion connection between said piston and said control member.

17. In combination, a hydraulic coupling having a working circuit for coupling liquid, a cylinder, a piston movable in said cylinder and forming therewith a liquid-storage chamber of variable capacity, a liquid-transfer duct between said chamber and said circuit, a gas vent between 40 said chamber and said circuit, and control means 45 for moving said piston.

18. In combination, a hydraulic coupling of the kinetic type having a working circuit for coupling liquid, a liquid outlet port, a fluid inlet port and means for discharging liquid from said circuit through said outlet port at a pressure exceeding the pressure at said inlet port, a liquid storage chamber, control means operable for varying the effective capacity of said chamber, a liquid transfer duct between said chamber and 50 said outlet port whereby liquid can be discharged from said circuit to said chamber, and a duct 55 communicating with said chamber and so positioned as to receive gas discharged with liquid from said circuit, said duct leading to said fluid inlet port.

HAROLD SINCLAIR.
